UNITED STATES PATENT OFFICE.

JOHN CLOUGH, OF HAINCLIFFE, NEAR KEIGHLEY, COUNTY OF YORK,
ENGLAND.

WOOL-WASHING MACHINE.

SPECIFICATION forming part of Letters Patent No. 251,833, dated January 3, 1882.

Application filed August 4, 1881. (No model.) Patented in England June 15, 1881.

To all whom it may concern:

Be it known that I, JOHN CLOUGH, a subject of the Queen of Great Britain and Ireland, and residing at Haincliffe, near Keighley, in the county of York, England, have invented certain Improvements in the Washing of Wool and other Fibers and in the apparatus therefor, (for which I have obtained provisional protection in Great Britain, No. 2,603, dated June 15, 1881,) of which the following is a specification.

The object of this my invention is to pass the fiber forward through the washing-bowls without the intervention of forks, hitherto in use for such purpose; and it consists in the arrangement of a series of reciprocating bars having spikes projecting forward in the direction in which the fiber is to travel and at an acute angle toward the sides of each bar. These bars form a false bottom within a trough which is within the ordinary washing-bowl, and are arranged so that while one half of the bars are moving—say in a forward direction—toward the squeezing-rollers the other half, each of which is placed alternately with one or other of the forward bars, are moving in the opposite direction. Thus by this reciprocating motion of the bars the spikes fixed therein carry the fiber through the suds or liquor in the washing-bowl to the ordinary lifting means.

In the accompanying drawings, Figure 1 represents a side elevation of an ordinary wool-washing machine, with one side of the bowl and trough removed in order to better illustrate my invention. Fig. 2 is a plan of the same, with the sides of the bowl and trough in position. Fig. 3 is an enlarged view of a portion of a bar, showing the direction in which the spikes project; and Fig. 4 is a plan of a few bars, showing the angle the spikes are set at.

The bowl of the washing-machine is indicated by the letter A, and is of ordinary construction, as are also the feeding-apron B and squeezing-rollers C and C', to which motion is communicated in the ordinary manner. Within the bowl A, I place a trough, D, extending the length of the said bowl and resting upon a number of carrying-plates, E, that are secured to the sides of the aforesaid bowl. Upon these plates E, and within the trough, are placed a series of bars, F and G, having spikes fixed thereto pro-

jecting forward toward the squeezing-rollers, and at such an angle sidewise that the points of the same, while they clear each other, are sufficiently near to enable the spikes on the forward bars to remove the shortest fiber from the spikes of the receding bars. These spikes are shown at F' and G' in detailed drawings, Figs. 3 and 4.

The fiber to be washed is fed onto the ordinary feeding-apron, B, which, traveling in the direction of arrow, delivers the same into end of trough D within the washing-bowl and becomes immersed in the suds contained therein by the projections H on the ordinary immersing-drum, which, revolving in the direction of arrow, presses the fiber down between the drum and guide-plate J. The spikes on the reciprocating bars F and G, which work under the guide-plate J, lay hold of the fiber and carry it forward in the manner as hereinafter described, the roller J', which is free to revolve on its axis, compressing any loose fiber down onto the spikes, and thus preventing the fiber floating on the surface of the suds.

The advantages of my arrangement of feed-bars along the bottom of the trough, in place of the ordinary rakes, are that the lumps of fiber are broken up, opened out, and distributed as the wool is passed from one end of the trough or washing-bowl to the other in the suds or washing-liquor. The wool is therefore more thoroughly washed and the fiber better prepared for the gill-boxes or carding-machines, inasmuch as the fiber being opened out, the hairs of the fiber are more in line with each other, or, in other words, the fiber is partly combed while passing through the suds in the washing-bowl.

Motion to the bars F and G is obtained in the following manner: On the main shaft K of machine I secure pinion K', which gears into wheel K², mounted on a stud secured to frame of machine. In the side of this revolving wheel I secure a crank-pin, L, which is connected by rod M to lever N, that is secured to shaft N', extending across the machine. To shaft N', I secure another lever, P, which is connected by rod P' to another lever, P². This last-named lever is secured to shaft P³, mounted in journals inside washing-bowl A, and near the opposite end of said shaft is another lever, P⁴, of

similar construction. To these levers are attached rods Q and Q', which are also attached to cross-bars S and S'. These cross-bars are arranged with a long slot-hole, S², through 5 which a projection, T, secured to each respective bar passes, so that when the machine is in motion the shaft N' will vibrate on its axis, and by means of the rods and levers connected therewith give a reciprocating motion to cross-bars S and S', and bars F and G, secured thereto, by the above-named projections T, the spikes F' and G' alternately carrying the fiber forward through the suds and delivering the same onto elevating-bars R, which are constructed and 10 actuated in the same manner as those before described, the latter bars delivering the fiber to the squeezing-rollers.

I am aware that alternately-reciprocating

toothed bars have been heretofore employed to lift the fibers out of the washing-liquor to the 20 squeezing-rolls; but this I do not claim.

I claim as my invention—

The combination of the trough of a wool-washing machine with a series of reciprocating toothed bars forming the bottom of the washing-space, and adapted to feed the fiber forward under the liquor in place of the ordinary overhead rakes, all substantially as and for the purpose set forth.

In testimony whereof I have signed my name 30 to this specification in the presence of two subscribing witnesses.

JOHN CLOUGH.
